UNITED STATES PATENT OFFICE.

FLORAIN J. SHOOK, OF AKRON, OHIO, ASSIGNOR TO THE B. F. GOODRICH COMPANY, OF NEW YORK, N. Y., A CORPORATION OF NEW YORK.

TANK VALVE.

Application filed July 19, 1922. Serial No. 576,028.

This invention relates to buoyant valves for flush tanks, and its object is to provide a rubber valve of improved form which may, if desired, be made by a simple method such as molding on a solid core and which shall possess the necessary air capacity and the necessary stiffness in its upper portion without resorting to extra reinforcing expedients, while its lower seating portion exhibits ample sealing properties through a long period of service.

Of the accompanying drawings, Fig. 1 is a side elevation of a preferred form of my improved valve.

Fig. 2 is a cross-section on the line 2-2 of Fig. 1, showing also the tank outlet in broken lines.

Fig. 3 is a reverse plan view.

The valve as shown is in one piece of, preferably, homogeneous vulcanized rubber, either of so-called floating stock or a stock which, by the incorporation of only small quantities of mineral matter, has a specific gravity approximating that of water.

Its lower or seating portion or head 10 is of conoidal or semi-spherical shape for seating within the funnel-shaped valve-seat 11 surrounding the tank outlet, while its upper portion or stem 12 is cylindroidal in form, being smaller in diameter at its lower end than the upper diameter of the seating portion and having a flattened top 13 in which is embedded the metal spud or anchorage 14 for screwing on the threaded lower end of the stem or rod 15.

The wall of the seating portion 10 is of downwardly-tapering cross-section, being thickest at its upper end where it merges into the wall of the upper portion 12 and shelves out beyond the latter. The interior air-chamber 16 is preferably formed by molding the valve around a metal core or mandrel, in which case the contracted mouth or opening 17 at the lower end of the valve is formed by the neck of said core and is of such diameter as to permit the withdrawal of the body of the core by stretching the mouth over it.

The described construction gives a vertically-elongated air-chamber of such capacity as to afford the necessary buoyancy to keep the valve off its seat, when lifted by the stem 15, during discharge of the contents of the tank. The upper portion 12, though of soft rubber and having no ribs or other usual

stiffening expedients, is prevented from collapsing under the head of water when the valve is seated, both because of its form and relatively small diameter and because of the stiffening effect afforded by the wall-thickness of the upper end of the seating portion 10, such thickness, however, being insufficient to interfere with a good sealing contact by conformity of said seating portion or valve proper with its seat. This sealing is promoted by a more direct transmission of the water pressure through the upper portion 12 to the zone of seating contact of the valve produced by a slight flattening of the portion 10 under the hydrostatic pressure, the base diameter of such upper portion being less, or at least no greater than the average diameter D of said zone.

It is found that one of the greatest advantages of this valve is that, although preferably of soft, flexible construction substantially throughout, it will not materially pull out of shape during long-continued use, a common fault with many of the older types of tank-balls, even when the top is made of semi-rigid or reinforced construction. This permanent deformation is avoided by the mushroom shape of my device, which I believe to be broadly new in a valve of substantially all-rubber, flexible construction. Said shape is conferred by the provision of a bulbous head as shown, in combination with a stem of smaller base diameter than the greatest diameter of the head, without reference to the particular shape of said stem. Another factor contributing to this improved result is the provision of an annular portion on the head 10, of uniform, maximum thickness at the junction of said head with the stem 12, in a full-molded valve made of stock which is at once soft and permanently resilient by reason of its high proportion of pure rubber.

It will be understood that the shape and other details may be somewhat varied without departing from my invention, and I do not exclude the use of ribbing or other usual reinforcement but merely say that my improved form of valve makes it non-essential.

In the valve here shown, an annular, upwardly-projecting flange or skirt 18 is molded around the upper margin of the seating portion 10 above the seating zone to shield the shelving edge of the valve from exposure to the outgoing stream of water adja-

cent to the point of highest velocity of said stream, with the object of delaying the closure of the valve, and also to constitute an upward extension of the valve proper which may be useful in connection with a relatively wide-mouthed valve-seat but this feature may be omitted without depriving the valve of its mushroom-shape characteristic and the resulting advantages.

19 I claim:

1. A buoyant tank valve of unitary, flexible, soft-rubber construction comprising a hollow lower or seating portion, and an upwardly-projecting, closed, cylindroidal stem of smaller diameter than said lower portion, forming substantially the upper half of the valve.

20 2. A flexible, buoyant valve of full-molded construction composed of substantially floating soft-rubber stock and having a hollow stem and a wide-mouthed, conoidal head integrally connected with and extending circumferentially beyond the lower end of said stem.

25 3. A buoyant tank-valve of mushroom shape having a flexible, soft-rubber, conoidal head and a hollow, cylindroidal stem vulcanized to said head at the back of the latter's seating zone.

20 4. A buoyant tank-valve of mushroom shape having a flexible, soft-rubber head, and a hollow stem having an integral connection with said head at the back of the latter's seating zone and flexibly formed of soft rubber at and adjacent to said connection.

40 5. A buoyant tank-valve of flexible, full-molded construction, composed of soft rubber stock and comprising a wide-mouthed, conoidal head and a hollow stem, said head including an annular portion of substantially uniform, maximum thickness at its junction with the stem.

45 6. A buoyant tank-valve of mushroom shape comprising a flexible, soft-rubber conoidal head having its region of greatest thickness at an intermediate seating zone,

and a hollow rubber stem vulcanized to the head at said region of greatest thickness.

7. A flexible, hollow, unitary tank-valve 50 of mushroom shape composed substantially throughout of soft vulcanized rubber, the head of said valve having its region of greatest thickness at its junction with the hollow stem of the valve at the seating zone 55 of said head.

8. A buoyant mushroom tank-valve comprising a hollow, cylindroidal stem, and a conoidal head of flexible, soft-rubber construction formed with an upwardly-projecting, 60 outer marginal flange.

9. A buoyant mushroom tank-valve of flexible, unitary, soft-rubber construction comprising a hollow, cylindroidal stem, and a conoidal head having its region of greatest 65 thickness where it joins said stem at the seating zone of the head, and formed with a thinner, upwardly-projective, outer marginal flange.

10. A buoyant mushroom valve having a 70 wide-mouthed, flexible rubber head and a hollow, cylindroidal rubber stem integrally vulcanized thereon.

11. A buoyant mushroom tank-valve comprising a stem, and a conoidal head of 75 flexible, soft rubber construction formed with an upwardly projecting, outer marginal flange.

12. A buoyant mushroom tank valve comprising a hollow stem, and a hollow, conoidal head of flexible, soft rubber construction formed with an upwardly projecting, outer 80 marginal flange.

13. A buoyant valve of integral, flexible, soft rubber construction comprising a hollow stem and a hollow seating portion enclosing a chamber provided with a wide opening at the bottom, and an upwardly projecting, annular, marginal upper lip on the seating portion. 85

In witness whereof I have hereunto set my hand this 13 day of July, 1922.

FLORAIN J. SHOOK.
